Primary Examiner — Elizabeth A. Albert(74) *Attorney, Agent, or Firm* — Baker & Hostetler LLP(57) **CLAIM**

The ornamental design for a writing instrument attachment, as shown and described.

DESCRIPTION

FIG. 1 is a perspective view of a writing instrument attachment in accordance with the present invention;

FIG. 2 is a front view thereof;

FIG. 3 is a rear view thereof;

FIG. 4 is a top view thereof;

FIG. 5 is a bottom view thereof; and,

FIG. 6 is a left side view thereof, the right side view being a mirror image.

The broken lines showing the character "A" in the FIGS. illustrate portions of the writing instrument attachment that form no part of the claimed design.
